J. A. B. SMITH

TYPEWRITING MACHINE

Original Filed Dec. 2, 1920

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed December 2, 1920, Serial No. 427,686. Renewed November 13, 1923.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and more particularly to the paper-controlling devices thereof, and is illustrated in the accompanying drawings as embodied in an Underwood standard typewriting machine.

15 In times past, it has largely been the practice to make out small bills, containing only a few lines, usually from one to three, with pen and ink, by reason of the fact that the large number of motions involved and the 20 amount of time consumed in inserting such bills around the platen and line-spacing them rendered their typing uneconomical. More lately, devices have been developed for 25 typing such bills, by which these bills could be inserted down past the printing line at the front of the platen and held in place by means of devices above the platen. The present invention relates more particularly to this last-mentioned kind of devices, and 30 has among its objects simplicity of construction, inexpensiveness of manufacture and effectiveness in operation.

The present invention provides a device for supporting a bill-sheet at the front of the platen in position to have a few lines typed on its bottom margin, and provides means whereby the bill-sheet may be adjusted to different line-space positions relatively to the printing line. Also means are 35 provided whereby the bill-sheet may be trued up relatively to the printing line or adjusted to compensate for variations in the printing of the bill-head. Also means are provided whereby bill-sheets of various 40 dimensions may be held for typing upon their bottom margins. Also provision is made for the quick insertion and removal or replacement of the successive bill-sheets upon which the typing is being done. The 45 typewriting machine may also include the usual line-spacing devices which co-operate with the platen, thereby providing for inde-

pendently line-spacing a record-sheet passing around the platen, to obtain a carbon-copy of the entries typed upon the bill- 55 sheet.

According to the present invention, the work-sheet or bill-sheet is held by its top margin upon a front paper-table or tablet by suitable sheet-holding means, such as 60 clips, and a leading-edge gage is provided which is mounted to be moved upwardly at line-space intervals, whereby the work-sheet held by the clips may be moved up to different line-space positions relatively to the 65 printing line, suitable means, such as a detent, being provided for holding or detaining the leading-edge gage at its different line-space positions.

As a more particular feature of the invention, the leading-edge gage, which may be in the form of a gage-plate extending down at the back of the tablet, is supported by means of inclined cams, so that, by pushing the gage-plate sidewise or laterally, it will 70 be raised by the cams to successive line-space positions and there held by the detent. The tablet and the sheet-holding clips co-operative therewith, and also the movable leading-edge gage, may all be mounted upon, and 75 carried by, a single supporting member, which, at its ends, is mounted for comparatively limited vertical adjustment upon 80 mounts to provide for the truing up and for small vertical adjustments of the leading-edge gage and other parts, said mounts, in turn, being adjustably mounted on 85 upstanding bars or uprights to occupy a plurality of positions at different heights for accommodating on the tablet work-sheets of 90 various dimensions and also for properly positioning, for successive days, ledger-sheets, or the like, on which the entries for successive days are made on successive lines.

Other features and advantages will here- 95 inafter appear.

In the accompanying drawings,

Figure 1 is a front elevation, with parts omitted, of the upper part of an Underwood typewriting machine, embodying the 100 present invention.

Figure 2 is a similar view, with other parts omitted, so as to show only what appears in the upper and central part of

Figure 1, and illustrates the leading-edge gage-plate as having been moved from its initial to its final line-space position.

Figure 3 is an enlarged partial front-to-rear vertical section on a plane indicated by the line 3—3 of Figure 1, as viewed from the left.

Figure 4 is a less enlarged end elevation, partly in section, as viewed from the left 10 in Figure 1.

Figure 5 is a partial plan view, with parts in horizontal section, and drawn about to the scale of Figure 3.

Figure 6 is a substantially horizontal section about to the scale of Figures 3 and 5 15 on a plane indicated by the line 6—6 of Figure 1, as viewed from above.

In carrying out the present invention, a work-sheet or bill-sheet 1 may be inserted 20 in the machine downward at the front of the usual rotative platen 2, past the printing line thereon, for having typing done upon its lower margin through the ribbon 3 by means of usual rearwardly and upwardly 25 swinging type-heads 4, of which one is shown in Figure 4. The bill-sheet 1, after being thus first moved downwardly, is then moved upwardly at the front of a front paper-table or tablet 5, into engagement with 30 sheet-holding devices in the form of spring-clips 6, co-operative with the tablet 5. The upward movement of the bill-sheet is continued until its upper or leading edge comes in contact with a leading-edge gage 7, which 35 projects above and to the front of the tablet 5 and which is shown as a forwardly-projecting flange formed along the upper edge of a gage-plate 8, which extends down at the back of the tablet 5. The tablet 5 is rigidly 40 supported upon a supporting member shown as a flat transverse bar 9, by means of a countersunk screw 10 adjacent to each end of the tablet 5, into the front of which the heads of the screws are countersunk, so as 45 to present a smooth outer surface. Also the countersinking of the screws 10 provides small offset portions 11 at the back of the tablet 5, thereby providing a space between the tablet 5 and its supporting bar 9 for the 50 accommodation of the gage-plate 8, which latter has inclined slotted openings 12 therein through which the offset portions 11 freely pass.

The gage-plate 8, carrying with it the 55 leading edge-gage 7, is movable upwardly by line-space intervals, in order thereby to provide for corresponding line-space movements of the bill-sheet 1, which is held on the tablet 5 by the spring-clips 6, and for 60 this purpose the gage-plate 8 is controlled by means of a cam-device now to be described. A pair of cam-pins or cam-studs 13 are fixed in and project forwardly from the supporting bar 9 into similar inclined

cam-slots 14 formed in the gage-plate 8, the 65 slots 14 being shown, as viewed from the front, as gradually inclined upwardly from the right towards the left. Each cam-slot 14 is shown as provided with a slight dwell 70 at each end thereof, to assist in retaining the gage-plate 8 at each of its final positions of line-space adjustment. In the construction shown in the drawings, the cam-slots 14 are of the proper length to provide 75 three line-space positions for the leading-edge gage 7, carried by the movable gage-plate 8. In this construction, if the gage-plate 8 be pushed sidewise or laterally from the right towards the left, the inclined cam-slots 14, co-operating with the cam-pins or 80 studs 13, will operate to raise the leading-edge gage 7 from its lowermost or initial position, shown in Figures 1, 3 and 4, successively, first to its intermediate or middle line-space position, and then to its final or 85 uppermost line-space position shown in Figure 2. Means are provided for detaining the gage-plate 8 at each of its three line-space positions, such means being illustrated 90 as a rounded spring-pressed detent-pin 15 passing from the rear through a hole in the supporting bar 9, and yieldingly engageable at its forward rounded end in any one of three similar holes or openings 16, 17 and 18, provided in the gage-plate 8. In order 95 to move conveniently the gage-plate 8 and leading-edge gage 7 carried thereby, back and forth, to and from different line-space positions, the leading-edge gage 7 at the right end thereof is provided with a rounded 100 upwardly-projecting handle, knob or finger-piece 19.

The construction is such that when the leading-edge gage 7 is at its lowermost or initial position shown in Figures 1 and 3 to 6, 105 inclusive, and when the upper or leading edge of the bill-sheet 1 is gaged against the leading-edge gage 7, then the lower margin of this sheet will be at the correct position for receiving the first line of typing at the printing line. After this first line has been written, then the finger-piece 19 may be pushed to the left, thereby causing the leading-edge gage 7 and gage-plate 8 to move along the cam-slots 14 to the left, and at the same time 110 upwards to the next or middle line-space position, the spring-pressed detent-pin 15 automatically becoming disengaged from the upper opening 16 and then snapping into the middle opening 17, where it operates to detain the gage-plate 8 and leading-edge gage 7 at the middle line-space position. The typist now grasps the bill-sheet 1 at its sides 115 near the top, and pulls it upward along the front of the tablet 5 beneath the spring sheet-holding clips 6, thereby to again gage or re-position the bill-sheet 1 with its leading edge 120 in contact with the leading-edge gage 7 at

its middle line-space position, at which new line-space position the bill-sheet 1 will be held on the tablet 5 by the clips 6, providing for the typing of the next successive or second line on the lower margin of this sheet. After the second line has been written, if desired, a next successive or third line may be typed below the second on the lower margin of the bill-sheet, by again pushing the finger-piece 19 to the left, resulting in moving the leading-edge gage 7 and gage-plate 8 further along from the middle to the lower ends of the cam-slots 14, the rounded end of the spring-pressed detent-pin 15 slipping out of the middle opening 17 in the gage-plate 8 and becoming automatically engaged in the lowermost or last opening 18, for thereby detaining the gage-plate 8 and leading-edge gage 7 at the uppermost or final line-space position thereof shown in Figure 2. Again the typist grasps the upper side margins of the bill-sheet 1 and adjusts this bill-sheet upward again into contact along its upper edge with the leading-edge gage 7, at which final line-space position the bill-sheet 1 will be held by the spring-clips 6 for the typing of a last or third line below the second along the lower margin of this sheet.

The upper corners of the tablet 5 are shown as cut away or hollowed out at 20, and also the upper right corner of the gage-plate 8 is shown as similarly cut away at 21, so that the typist may more easily be enabled to grasp the bill-sheet 1 for moving it to successive line-space positions. In the particular construction shown in the drawings, the detent-pin 15 is shown as provided at the back of the support 9 with a shoulder or collar 22, and is guided by a small flanged cap or cup 23 secured to the back of the support 9, a coiled detent spring 24 being interposed between the inner side of this cap and the shoulder 22 on the detent-pin 15.

For positioning the gaged bill-sheet 1 laterally a side gage 25 is provided, and is shown in the drawings as formed by a forwardly-turned vertical flange at the left end of the tablet 5. It is obvious that the gaging position of this side gage 25 will not be affected by the combined lateral and upward line-space movement of the leading-edge gage 7.

In order to make a record of what is typed on the lower margin of the bill-sheet 1, a suitable record-sheet 26, together with a carbon-sheet 27 at the outside thereof, may be passed down at the front of an inclined rear paper-table 28, below and up around the platen 2, and thence passed upward and rearward between the platen 2 and the lower edge of the tablet 5 to the rear of the latter; the record-sheet 26 and the carbon-sheet 27 also passing between the platen and the lower margin of the bill-sheet 1 at the printing line,

as shown in Figure 4. The record-sheet 26 and carbon-sheet 27 are pressed towards and into line-feeding relation with the platen 2 by means of front and rear sets of releasable feed-rolls 29 and 30, which may be released or cast off by the usual or any suitable cast-off mechanism, of which the usual finger-piece 31 is shown in Figure 1.

Line-feeding movement may be imparted to the record-sheet 26 and carbon-sheet 27 independently of the short front-inserted bill-sheet 1 by means of the usual or any suitable line-space mechanism, shown as including the usual pivoted line-space handle 32 and slide 33 which carries a line-spacing pawl 34 cooperative with a line-space wheel 35 fixed on the platen axle 36, which is journaled in end plates 37 of the usual shift-frame or platen-frame which includes the rear paper-table 28. The line-space movements of the platen 2 may be varied to move either one, two or three line-spaces, as may be desired, by manipulating the usual line-space control-handle 38. By reason of the independent line - spacing or line - feeding movement of the record-sheet 26, it will be evident that, if desired, the lines typed upon the record-sheet 26 may be spaced differently, either wider or closer, than the lines typed upon the lower margin of the bill-sheet 1. It is to be understood that, if desired, the record-sheet 26 may be of different form. For example, the record-sheet 26 and the carbon-sheet 27 could be in the form of continuous strips, unrolled from one spool and wound upon another spool, so that the record-sheet may form a tally-strip or continuous proof-sheet, as is well known in the art.

It is also to be understood that the machine of the present invention is adapted to accommodate bill-sheets of other kinds, different from the short front-inserted bill-sheet 1. For example, a bill-sheet of greater length could be inserted around the platen from the back down at the front of the rear paper-table 28, outwardly from the carbon-sheet 27, so as to come up past the printing line at the front of the platen. In such case, this more lengthy bill-sheet, together with the record-sheet 26, if desired, could be gaged at its leading edge against the leading-edge gage 7. For this class of work, the sheet-holding clips might not be needed, and therefore provision is made for detaching these clips. The clips 6 have attaching shanks which extend down at the back of the supporting bar 9 and are removably secured in place by means of thumb-screws 39, and are held against angular movement by dowel pins 40 projecting from the supporting bar 9 through the ends of the shanks of the clips 6.

In order to provide for the free and un-

obstructed upward line-space movement of the leading-edge gage 7, the clips 6, as they turn forward and downward on a curve, are carried some distance in spaced relation above the leading-edge gage 7, thereby allowing for the full movement of the leading-edge gage 7 from its lowermost line-space position, shown in Figures 1, 3 and 4, to its uppermost line-space position, shown in Figure 2.

The leading-edge gage 7 and other associated parts mounted on the supporting bar 9, and including the tablet 5 and the clips 6, are provided with means for adjustment whereby they may be trued up relatively to the printing line or adjusted to compensate for slight variations of the printing of the headings of the bill-sheets. For this purpose, the supporting bar 9 is adjustably supported at its ends on mounts 41 by means of screws 42 passing through vertical slots 43 in the bar 9 and screwing into the mounts 41. This adjustment by means of the screws 42 and slots 43 does not vary the working position of the tablet 5, clips 6 and leading-edge gage 7, but, as above noted, merely provides for effecting slight adjustments of these parts relatively to the printing line. Provision is also made, however, to change or adjust the working position of the leading-edge gage 7 and other parts carried by the supporting bar 9, including the tablet 5 and clips 6, so that these parts may occupy a plurality of working positions at different heights relatively to the printing line, for thereby accommodating bill-sheets having heads of various lengths, or for positioning, for successive days, ledger-sheets, or the like, on which entries for successive days are made on successive lines. For this purpose, the mounts 41 are adjustably secured upon rearwardly-inclined uprights 44 by means of thumb-screws 45 passing through the mounts 41 and adapted to screw into any one of a series of uniformly-spaced holes 46 in each of the uprights 44. This arrangement also provides for gaging and typing entries from time to time upon long bill-sheets on statements passed around the platen 2, as hereinbefore described. The holes 46 may be at single line-space intervals in the uprights 44, and settings for successive days may be at double or triple line-space intervals. If it is desired to make entries of more than one line on a work-sheet upon the given day, the leading-edge gage 7 may be shifted a single line-space at a time by means of the finger-piece 19. During such shifting of the leading-edge gage 7, the work-sheet 1 will be held against the collating table 5 by means of a clip 6, and, upon completion of the movement of the leading-edge gage 7, the work-sheet 1 may be grasped and positioned against the gage.

The uprights 44 are supported upon the platen-frame or shift-frame. Near their lower ends the uprights 44 are secured by means of screws 47 to forwardly-extending arms on brackets 48. The brackets 48 are mounted on transverse rods, shown in the drawings as comprising a lower rod 49 extending from side to side between the end plates 37 of the platen-frame, and an upper rod 50 supported at its ends in end brackets 51 secured by screws 52 on the end plates 37 of the platen-frame. Below their upper ends, the uprights 44 are further supported and braced by ends 53 of rearwardly and downwardly extending braces 54, the lower ends of which are secured to short rearwardly inclined supports 55 which are held in place on the platen-frame ends 37 by the above-mentioned screws 52.

Variations may be resorted to within the scope of the invention, and portions of the improvements may be used without others.

Having thus described my invention, I claim:

1. In a front-strike typewriting machine, the combination with a platen, of a paper-table or tablet at the front of the platen above the printing line, means for holding a work-sheet on the tablet, a leading-edge gage for the work-sheet, a finger-piece, finger-piece actuated means for shifting said leading-edge gage relatively to the tablet and said sheet-holding means, whereby the work-sheet may be adjusted on the tablet to different line-space positions, and means for detaining said leading-edge gage at its different line-space positions.

2. In a front-strike typewriting machine, the combination with a platen, of a tablet at the front of the platen above the printing line and mounted to occupy a plurality of working positions at different heights relatively to the printing line for accommodating work-sheets of various dimensions, a leading-edge gage movable relatively to the tablet to different line-space positions for gaging or positioning a work-sheet on the tablet at correspondingly different line-space positions relatively to the printing line, and sheet-holding means having a fixed mounting relatively to and co-operative with the tablet for holding the gaged work-sheet thereon.

3. In a front-strike typewriting machine, the combination with a platen-frame and a platen journaled therein, of uprights on the platen-frame, a tablet-support adjustably mounted on the uprights to occupy a plurality of positions at different heights so as to accommodate work-sheets of various dimensions, a tablet mounted upon said support at the front of the platen above the printing line, means for holding a work-sheet on the tablet, and a leading-edge gage

- movable to different line-space positions relatively to the tablet and said sheet-holding means, whereby the work-sheet may be adjusted to correspondingly different line-space positions on the tablet and relatively to the printing line.
4. In a front-strike typewriting machine, the combination with a platen, of a paper-table or tablet at the front of the platen above the printing line, means for holding a work-sheet on the tablet, a leading-edge gage for the work-sheet movable by line-space intervals relatively to the tablet and said sheet-holding means, whereby the work-sheet may be adjusted to correspondingly different line-space positions on the tablet and relatively to the printing line, a pin-and-cam device for moving the leading-edge gage to different line-space positions, and a detent for detaining the leading-edge gage at its different line-space positions.
5. In a front-strike typewriting machine, the combination with a platen, of a paper-table or tablet at the front of the platen above the printing line, means for holding a work-sheet on the tablet, a leading-edge gage for the work-sheet movable by line-space intervals relatively to the tablet and said sheet-holding means, whereby the work-sheet may be adjusted to correspondingly different line-space positions on the tablet and relatively to the printing line, a device for supporting the leading-edge gage and for moving the leading-edge gage to different line-space positions when it is pushed laterally of the machine, and a detent for detaining the leading-edge gage at its different line-space positions.
6. In a front-strike typewriting machine, the combination with a platen, of a paper-table or tablet at the front of the platen above the printing line, means for holding a work-sheet on the tablet, a leading-edge gage for the work-sheet movable by line-space intervals relatively to the tablet and said sheet-holding means, whereby the work-sheet may be adjusted to correspondingly different line-space positions on the tablet and relatively to the printing line, an inclined cam-slot-and-pin device for supporting the leading-edge gage and for moving the leading-edge gage to different line-space positions when it is pushed laterally of the machine, a detent for detaining the leading-edge gage at its different line-space positions, and a side gage for the work-sheet and relatively to which the leading-edge gage is movable.
7. In a front-strike typewriting machine, the combination with a platen, of a paper-table or tablet at the front of the platen above the printing line, clips fixedly mounted relatively to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, and a cam device comprising inclined slots and pins engaging therein for supporting the gage-plate so that when the gage-plate is pushed laterally it will be moved to different line-space positions.
8. In a front-strike typewriting machine, the combination with a platen, of a paper-table or tablet at the front of the platen above the printing line, clips fixedly mounted relatively to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, a cam device comprising inclined slots and pins engaging therein for supporting the gage-plate so that when the gage-plate is pushed laterally it will be moved to different line-space positions, and a detent for detaining the gage-plate at its different line-space positions.
9. In a front-strike typewriting machine, the combination with a platen, of a paper-table or tablet at the front of the platen above the printing line, clips fixedly mounted relatively to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, a cam device for shifting the gage-plate to different line-space positions, a detent for detaining the gage-plate at its different line-space positions, and a side gage for the work-sheet and relatively to which the leading-edge gage is movable.
10. In a front-strike typewriting machine, the combination with a rotative platen and feed-rolls therefor for holding a record-sheet thereon, of a line-spacing mechanism for the platen, a paper-table or tablet at the front of the platen above the printing line and separated from the platen to permit the record-sheet to feed between the tablet and the platen, clips fixedly mounted relatively

- to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, and means for detaining the gage-plate at its different line-space positions.
11. In a front-strike typewriting machine, the combination with a platen-frame and a platen journaled therein, of uprights on the platen-frame, a paper-table or tablet at the front of the platen above the printing line, a tablet-support adjustably mounted on the uprights, so that the tablet may occupy a plurality of working positions at different heights for accommodating work-sheets of various dimensions, clips fixedly mounted relatively to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, and a detent for detaining the gage-plate at its different line-space positions.
12. In a front-strike typewriting machine, the combination with a platen-frame and a platen journaled therein, of feed-rolls for holding a record-sheet on the platen, a line-spacing mechanism for the platen, a paper-table or tablet at the front of the platen above the printing line and separated from the platen to permit the record-sheet to feed between the tablet and the platen, uprights on the platen-frame, a support for the tablet adjustably mounted on the uprights, so that the tablet may occupy a plurality of working positions at different heights for accommodating work-sheets of various dimensions, clips fixedly mounted relatively to the tablet for engaging the leading-edge margin of a work-sheet to hold it on the tablet, a gage-plate at the back of the tablet and provided at its upper edge with a leading-edge gage for the work-sheet, said gage-plate being mounted for movement relatively to the tablet to different line-space positions, whereby the work-sheet held by the clips may be moved up on the tablet to different line-space positions relatively to the printing line, a cam device comprising inclined slots and pins engaging therein for supporting the gage-plate so that when the gage-plate is pushed laterally it will be moved to different line-space positions, and a detent for detaining the gage-plate at its different line-space positions.
13. In a front-strike typewriting machine, the combination with a platen, of a paper-table or tablet at the front of the platen above the printing line, means for holding a work-sheet on the tablet, a leading-edge gage for the work-sheet movable by line-space intervals relatively to the tablet and said sheet-holding means, whereby the work-sheet may be adjusted on the tablet to different line-space positions relatively to the printing line, a detent for detaining the leading-edge gage at its different line-space positions, and means for adjustment whereby the tablet and the sheet-holding means and the leading-edge gage may all be trued up relatively to the printing line or adjusted to compensate for variations of the printing of the work-sheet.
14. In a front-strike typewriting machine, the combination with a platen, of a paper-table or tablet at the front of the platen above the printing line, means for holding a work-sheet on the tablet, a leading-edge gage for the work-sheet movable by line-space intervals relatively to the tablet and said sheet-holding means, whereby the work-sheet may be adjusted on the tablet to different line-space positions relatively to the printing line, means for detaining the leading-edge gage at its different line-space positions, supporting means for the tablet provided with means for adjustment whereby the tablet and the sheet-holding means and the leading-edge gage may all be trued up relatively to the printing line or adjusted to compensate for variations of the printing of the work-sheet, and a support upon which said supporting means are mounted to occupy a plurality of positions at different heights so as to accommodate on the tablet work-sheets of various dimensions.
15. In a front-strike typewriting machine, the combination with a platen-frame and a platen journaled therein, of a paper-table or tablet at the front of the platen above the printing line, means for holding a work-sheet on the tablet, a leading-edge gage for the work-sheet movable by line-space intervals relatively to the tablet and said sheet-holding means, means for detaining the leading-edge gage at its different line-space positions, uprights on the platen-frame, tablet-supporting mounts adjustably mounted on the uprights to occupy a plurality of positions at different heights for accommodating on the tablet work-sheets of various dimensions, and a supporting member for the tablet adjustably mounted on said mounts and whereby the tablet and the sheet-holding means and the leading-edge

gage may all be trued up relatively to the printing line or adjusted to compensate for variations of the printing of the work-sheet.

16. In a front-strike typewriting machine, the combination with a platen, of a paper-table or tablet at the front of the platen above the printing line, a supporting member to the front of which the tablet is secured, a gage-plate at the back of the tablet and provided at its upper edge with a leading-edge gage projecting above and to the front of the tablet to be engaged by the leading edge of a work-sheet on the tablet, clips mounted upon said supporting member and passing in spaced relation above the gage-plate and down at the front of the tablet for engaging the leading-edge margin of the work-sheet to hold it on the tablet, inclined cam-slot-and-pin connections between the gage-plate and said supporting member for moving the gage-plate to different line-space positions when it is pushed laterally, and a detent mounted on said supporting member and engageable in openings in the gage-plate for detaining the gage-plate at its different line-space positions.

17. In a front-strike typewriting machine, the combination with a revoluble platen, of a collating table at the front of the platen above the printing line, a leading-edge gage associated with said collating table, and means for shifting said leading-edge gage in a line-space direction by pressing it in a direction perpendicular to the line-space direction.

18. In a front-strike typewriting machine, the combination with a revoluble platen, of a collating table at the front of the platen above the printing line, a leading-edge gage associated with said collating table, parallel-motion means for shifting said leading-edge gage in a line-space direction by pressing it in a direction perpendicular to the line-space direction, and detent means effective to hold said leading-edge gage only in predetermined line-space positions.

19. In a typewriting machine, in combination, a revoluble platen, a collating table at the delivery side thereof, a leading-edge gage associated with said table and adjustable with respect thereto, and clips to press against the table the leading ends of work-sheets placed thereon, said clips being supported in fixed relation to said table.

20. In a typewriting machine, in combination, a revoluble platen, a collating table at the delivery side thereof, a leading-edge gage associated with said table and adjustable with respect thereto, and clips to press against the table the leading ends of work-sheets placed thereon, said clips being fixed to said table at the back thereof and curved over the upper edge of the table in

loops, so that their ends will engage the front face of the table and the loops will permit the desired movement therein of said leading-edge gage with reference to the table.

21. In a typewriting machine, the combination of a platen, a collating table at the delivery side of the platen, a leading-edge gage adjacent the upper edge of the collating table and adjustable to different positions relative thereto, and means to hold work-sheets in position on said table comprising spring members fixed to the table at the rear thereof and extending around the forward edge thereof in loops, so as to engage the table at points spaced from the upper edge of the latter and to permit movements of said leading-edge gage within the loops formed by said spring members.

22. In a typewriting machine, the combination with a platen, of a collating table adjacent thereto, an end gage associated with the collating table, and means for shifting said end gage relatively to the collating table and in a line-feed direction, said shifting means including a pin-and-inclined-slot connection between the end gage and the collating table, so that manual movement of the gauge transversely of the machine will cause it to be moved in a line-space direction relatively to the collating table.

23. In a front-strike typewriting machine, the combination with a platen, of a collating table, means for setting said table in different positions for different successive days and comprising upwardly-extending members having openings at single line-space intervals and set-screws connected with the table and provided with suitable ends to fit said openings, a leading-edge gage shiftable on said table, and means for line-spacing said leading-edge gage, so that, when the settings for successive days are at intervals of a plurality of single line-spaces, the leading-edge gage may be line spaced single line-spaces for gaging a work-sheet for typing a plurality of lines at single line-space intervals in the space reserved for a single day.

24. In a typewriting machine, a platen, and collating means associated therewith comprising a collating table having inclined slots and a leading-edge gage, and pins projecting into said slots so that lateral pressure on the table will cause the latter to be cammed in a line-space direction.

25. In a typewriting machine, a paper-table, springs supported at the rear of the table and arched around the leading edge of the table to engage the latter at points spaced from its leading edge, and a leading-edge gage extending transversely of the table within the arched portions of the

springs and adjustable to different positions in line-space direction.

26. In a typewriting machine, a paper-table, springs supported at the rear of the table and arched around the leading edge of the table to engage the latter at points spaced from its leading edge, a leading-edge gage extending transversely of the table within the arched portions of the springs

and adjustable to different positions in line-space direction, and cam connections between said gage and said table for shifting said gage with reference to the table. 10
